COMBINATION HOLDER AND COMB

Diamond P. Califano, Amsterdam, N. Y.

Application April 17, 1939, Serial No. 268,402

3 Claims. (Cl. 132—11)

The present invention relates to a combination holder and comb and more particularly to the type employed by hairdressers, beauticians and the like.

One of the objects of the present invention is to provide a comb holder in which the regulation hairdresser's comb may be removably secured.

A still further important object of the invention is to provide a comb holder of this character having a magnetized portion permitting of the hairdresser to pick up, place in the hair and remove therefrom the hairpins which are used during the process of permanent waving and the like.

A still further attribute of the invention will be found to reside in the novel slidable handle construction and arrangement in the holder permitting the same to be used by specialists as a handle, or for smoothing, stretching and making cluster curls or the like, while at the same time being adapted to be telescopically inserted within the holder so that the combination comb may be handily carried in the pocket or purse if so desired.

In combination with the holder, there will be found a novel key arrangement for tightening or loosening Croquignole rods or curlers employed in the hairdressing art.

A still further important object of the invention is to provide a comb holder, which is constructed with a novelly arranged slidable curling iron.

Another important attribute of the invention will be found to reside in the novelly constructed comb having in combination therewith a blade for cutting the hair or loose ends if so desired.

A still further important object of the invention is to provide a comb holder which has a slidable handle therein which may function if so desired as a fingernail file.

In the accompanying drawings wherein for the purpose of illustration there is shown a preferred embodiment of the invention, and in which corresponding parts are designated by similar reference numerals,

Figure 1 is a front elevational view of the combination holder and comb,

Figure 2 is a top plan view thereof,

Figure 3 is a fragmentary horizontal sectional view of Figure 1,

Figure 4 is a vertical sectional view of Figure 1 taken on line 4—4 thereof,

Figure 5 is a fragmentary vertical sectional

view of the device showing the handle in its extended operative position.

Figure 6 is a vertical sectional view of Figure 5 taken on line 6—6 thereof,

Figure 7 is a fragmentary end elevational view of the holder showing the key portion of the device,

Figure 8 is a modified form of the invention showing a holder or cap adapted for use on the well known rat-tail comb, and

Figure 9 is a vertical sectional view of Figure 8 taken on line 9—9 thereof.

In the accompanying drawings wherein for the purpose of illustration there is shown preferred embodiments of the invention reference numerals 10 and 12 generally designate oppositely disposed side portions of the comb holder. As will be observed they are of general rectangular shape, being provided with a raised upper portion having downwardly and outwardly inclined side portions 16 and 18. Each of the sides 10 and 12 at the forward ends thereof are provided with substantially reduced rectangularly shaped projections or prongs 20 defining keys for tightening or loosening Croquignole rods or curlers used in the art.

Between the upper portions of the sides 10 and 12 there is disposed a magnetized member 22. This magnetized member, as illustrated in Figure 3, has its upper side portions of substantially the same configuration as the upper side portions of the members 10 and 12 and is provided with a flat bottom and a depending stop member 26 on its forward end. One of the upper inclined edges of the magnetizable member 22 is serrated defining a nail file. One of the side members 12 is secured to one side of the magnetizable member by welding or the like while to the other side of the magnetizable member 22 there is secured a substantially L-shaped spring member 28, the short arm of which is disposed in spaced relationship to the bottom portion of the magnetizable member defining what may be termed a longitudinally extending socket in which the handle 32 is telescopically received. To the outer side of the spring member 28 by welding or the like the other side 10 of the holder is secured. It will be observed that adjacent the innermost end of the L-shaped member 28 the same is provided with a spring catch 34 which is receivable in a notch 36 in the handle 32, so that when the handle 32 is pulled outwardly the notch 36 receives the spring prong 34 preventing the handle from being en-

tirely removed and locking the same in operative combing position. This handle is of substantially rectangular shape in vertical cross-section having the edges rounded thereof so that the same in its extended position in the art may be used for smoothing, stretching and making sculptural curls.

Adjacent the lowermost longitudinally extending edge of the oppositely disposed sides 10 and 12 there are provided inwardly directed integral flanges 40 and 42 which terminate in spaced relationship and are adapted to be received in the regulation hairdresser's comb which is slid between the sides 10 and 12 of the holder. This comb 44 has its upper side in abutting contact 10 with the lower portion of the spring member 28 15 and on its lower edge there is provided the usual integral depending teeth 46.

It will thus be seen that the holder is provided with a magnetizable member therein which may be used to pick up, place in the hair and remove therefrom the hairpins which are used during the process of permanent waving, permitting of a speedy and neat removal thereof without effecting a disarrangement of the sculptured curls. The telescopically arranged handle not only facilitates the combing, but provides a means for smoothing and stretching the hair in the making of a curl as well as permitting of the device to be used as a pocket comb. The keys or prongs 20 provide a unique and novel arrangement for tightening or loosening the Croquignole rods or curlers.

Obviously the opposed sides 10 and 12 of the holder may be constructed of any type material desired such as a non-tarnishable nickel steel of any durability which will removably receive the comb 44.

Referring now to Figure 8 it will be seen that there is illustrated a modified form of the invention in which, a holder or cap is provided for the usual rat-tail comb. In this form of the invention as shown in Figures 8 and 9 the oppositely disposed sides 50 and 52 have arranged therebetween the magnetizable upper portion 54 which is secured therein by means of pins 56 or the like. The sides 50 and 52 are provided adjacent the lower longitudinal edge on the inner side thereof with inwardly directed integral flanges 58 which are received in oppositely disposed longitudinally extending grooves 60 in the rat-tail

comb. Thus, as shown in Figure 8, the rat-tail comb as hereinbefore described with respect to the comb 44 is slid between the sides 50 and 52 with the longitudinally extending grooves receiving the flanges 58 thereby firmly securing the holder to the comb. Of course, if so desired, the flanges may be dispensed with and the cap held on the comb merely by the contacting pressure.

While there is shown for the purpose of illustration preferred embodiments of the invention it is to be understood that it is capable of various changes and modifications without departing from the spirit and scope thereof and it is intended therefore that only such limitations shall be imposed thereon as are indicated in the prior art or in the appended claims.

What is claimed is:

1. A comb holder comprising a pair of side members, a magnetic member interposed between the upper portions thereof being secured thereto and holding said side members in spaced relationship, said holder being adapted to receive a comb between the side members.

2: In combination, a support comprising a pair of spaced side members, means disposed between the upper portion of said members securing the same together, oppositely disposed longitudinally extending flanges on the inner sides of said members terminating short of one another and adapted to be received in corresponding longitudinally extending grooves in a comb slidably inserted between said side members, said support being provided with a longitudinally extending socket in the upper portion thereof and receiving a handle, a handle slidable therein, and resilient means cooperating with said handle for securing the same in a pre-determined operative position.

3. In combination, a support comprising a pair of spaced side members secured together at their upper portions, means on the inner sides of said members for slidably securing a comb between said side members, the upper portion of said support being provided with a longitudinally extending slot therein, a handle slidable in said slot, said handle being provided adjacent its inner end with a notch, and resilient means in said slot adjacent the outer end thereof for engagement with said notch for holding said handle in pre-determined operative position.

DIAMOND P. CALIFANO.
